UNITED STATES PATENT OFFICE.

WESLEY C. BUSH, OF BROOKLYN, NEW YORK.

FIRE-ESCAPE LADDER.

SPECIFICATION forming part of Letters Patent No. 275,135, dated April 3, 1883.

Application filed November 11, 1882. (No model.)

To all whom it may concern:

Be it known that I, WESLEY C. BUSH, of Brooklyn, in the county of Kings and State of New York, have invented a new and Improved 5 Fire-Escape Ladder, of which the following is a full, clear, and exact description.

The object of my invention is to provide a new and improved fire-escape ladder which can be wound upon a drum, which ladder is 10 flexible in one direction and stiff in the other, and which is provided at its lower end with a foot-piece which automatically adjusts itself on the ground and forms a support for the ladder.

15 Reference is to be had to the accompanying drawings, forming a part of this specification, in which similar letters of reference indicate corresponding parts in all the figures.

Figure 1 is a longitudinal elevation of my 20 improved flexible ladder and foot-piece, showing the foot-piece hanging from the lower end of the ladder, parts being shown in section. Fig. 2 is a like longitudinal elevation, showing the foot-piece resting on the ground. Fig. 3 25 is a front elevation of the ladder and foot-piece in the position shown in Fig. 1. Fig. 4 is an enlarged detail longitudinal elevation of the joint-piece. Fig. 5 is an end elevation of the same.

30 The ladder is formed of two side pieces, A, connected by rung-bars B, which are placed suitable distances apart, the said side pieces being formed of a series of segmental or truss-shaped links, which are united by pivots passed 35 through the ends of the said link-pieces, the side surfaces of the ends of the link-pieces resting against each other. As shown in Fig. 3, three and four link-pieces are united alternately; but more or less may be coupled 40 together, as may be desired, according to the length and required strength of the ladder. A U-shaped joint-piece, E, which has its ends beveled or recessed to make it very light, is passed over the ends of the links, and the 45 coupling-pins D are passed through the end shanks of the said joint-pieces E. The ladder is to be attached to the house in such a manner that the concave edges of the links will be toward the house and the convex edges 50 from the house, and the cross-pieces of the joint pieces are to pass over the ends of the

convex edges of the links. The ladder can fold toward the side of the concave edges of the links, but cannot fold toward the side of the convex edges of the links, and thus is stiff in 55 that direction, and, when lowered, stiffens itself automatically because of the cross-pieces of the joint-pieces E, against which the ends of the convex edges of the links strike. To the lower rung-bar B a series of long links, C', 60 are pivoted, and to the same a series of bars, F, are pivoted, the outer ends of the outer bars F being united by a heavy block or casting, G. Curved bars H are pivoted to the innermost of the bars F, and are each provided 65 with a longitudinal slot, J, through which a pin, K, passes, which projects from the innermost of the long links C'. Directly below the slot the lower curved edge of each curved bar H is provided with a series of teeth, L, which 70 are adapted to catch on a pin, M, projecting from the inner surface of the innermost long link C'. A spring, N, attached to the inner surface of the innermost long link C', rests on the upper curved edge of the curved 75 bar H and presses the toothed edge on the pin M. The lower end of each bar H is provided with a broad foot-piece, which is adapted to rest on the ground, preventing it from moving forward or backward. A stud, O, projects 80 from the outer surface of the outermost long link C' at the lower ends of the same, against which stud O the upper edges of the pivoted ends of the outermost bars F are adapted to strike to prevent the long links C' from folding 85 over the bars F. A joint-piece, P, resembling the joint-pieces E, is attached to the lower ends of the lowest links C', but on the opposite side of the latter to that on which the joint-pieces E are secured, which joint-piece P, in 90 addition to the studs O, holds the lowest links C' erect on the ends of the bars F.

The above-described ladder is adapted to be wound on a drum on the top of a house, and is to be released in case of fire. The heavy 95 block G draws the ladder downward until the said block G strikes the ground, and then the pivoted ends of the bars F and the ends of the long links C' strike the ground. Thereby the bars F will be drawn in the position as shown 100 in Fig. 2, the foot ends of the curved bars H rest on the ground, the teeth L slide over the

stud M, and, finally, one of the teeth catches on the same and holds the said parts in position. The foot thus formed supports the ladder, and removes much of the strain from the pivots of the drum to which the ladder is secured. It 5 also prevents the swinging of the ladder and holds the same in the proper position. If the ladder is to be wound on the drum again, the upper end of the bars H must be raised to dis- 10 engage the teeth L from the studs M. The links C' are to be made of wrought-iron, and the joint-pieces E P can be made of wrought-iron, or of cast-iron, or any other suitable metal, as may be desired.

15 The above-described ladder is very simple in construction, is very durable, and is fully adapted to be wound on a drum.

The above-described ladder is designed for use as a fire-escape ladder, but can be used for 20 any other purpose for which a flexible ladder is used.

I am aware that it is not broadly new to form the sides of a fire-escape ladder of curved links having each end pivoted to a rung; but

25 What I do claim as new is—

1. In a flexible fire-escape ladder, the combination, with a series of segmental or truss-shaped links, C', pivoted to each other, of the U-shaped joint-pieces E, through the ends of 30 which the pivots or rung-bars pass, substantially as herein shown and described, and for the purpose set forth.

2. The combination, with a flexible ladder, of a foot-piece formed of bars F, pivoted to the 35 lowest links, and of bars H, pivoted to the bars F and adapted to be held to the lowest links, substantially as herein shown and described, and for the purpose set forth.

3. The combination, with a flexible ladder, 40 of the bars F, pivoted to the lowest links, the weighted cross-piece G, the bars H, pivoted to the bars F and adapted to be held to the lowest links, substantially as herein shown and described, and for the purpose set forth.

4. The combination, with a flexible ladder, 45 of the bars F, pivoted to the lowest links, the curved bars H, each provided with a slot, J, and the studs K, projecting from the lowest links, substantially as herein shown and described, and for the purpose set forth. 50

5. The combination, with a flexible ladder, of the bars F, pivoted to the lowest links, the curved bars H, each provided with a slot, J, and the teeth L, and the studs K and M, substantially as herein shown and described, and 55 for the purpose set forth.

6. The combination, with a flexible ladder, of the bars F, pivoted to the lowest links, the curved bars H, pivoted to the bars F, and each provided with a slot, J, and teeth L, the studs 60 K and M, and the springs N, substantially as herein shown and described, and for the purpose set forth.

7. The combination, with a flexible ladder, of the bars F, pivoted to the lowest links, and 65 the studs O, projecting from the outer surfaces of the lowest links at the lower ends of the same, substantially as herein shown and described, and for the purpose set forth.

8. The combination, with a flexible ladder, 70 of a foot-piece, of bars pivoted to the lowest links, and of brace-bars having the lower ends widened or enlarged and pivoted to the bars which are pivoted to the lowest links, the said brace-bars being adapted to be held on 75 the lowest links, substantially as herein shown and described, and for the purpose set forth.

9. In a flexible ladder, the combination, with the bars F, pivoted to the lowest links, and of the joint-piece P, secured over the joints of 80 the bars F and the lowest links C', substantially as herein shown and described, and for the purpose set forth.

WESLEY C. BUSH.
